COMBINATION UTILITY HOOD AND LOUNGER OR THE LIKE Frank W. Derenski, 11009 Morrison St.,
Los Angeles, Calif. 91601

Filed June 14, 1967, Ser. No. 7,469

Term of patent 14 years

(Cl. D14—27)

FIGURE 1 is a front perspective view of a combination utility hood and lounger or the like embodying my new design;

The outline of a portion of an automobile is shown in phantom lines in FIGURE 1 for illustrative purposes only.

I claim:

The ornamental design for a combination utility hood and lounger or the like, as shown and described.
